UNITED STATES PATENT OFFICE

WALTER DORWIN TEAGUE, OF FOREST HILLS, NEW YORK, ASSIGNOR TO TAYLOR INSTRUMENT COMPANIES, OF ROCHESTER, NEW YORK, A CORPORATION OF NEW YORK

DESIGN FOR A COMBINED THERMOMETER AND BRACKET

Application filed January 21, 1933. Serial No. 46,916. Term of patent 3½ years.

To all whom it may concern:

Be it known that I, WALTER DORWIN TEAGUE, a citizen of the United States of America, residing at Forest Hills, county of Queens, State of New York, have invented a new, original, and ornamental Design for a Combined Thermometer and Bracket, of which the following is a specification, reference being had to the accompanying drawing, wherein:

Fig. 1 is a side view of the thermometer

bracket and a front view of the thermometer supported therein;

Fig. 2 is a front view of the thermometer bracket; and

Fig. 3 is a sectional view of the thermometer taken on the line 3—3 of Fig. 1.

I claim:

The ornamental design for a combined thermometer and bracket as shown.

WALTER DORWIN TEAGUE.
